[57] **CLAIM**

The ornamental design for a combined hand and finger shield, as shown and described.

DESCRIPTION

FIG. 1 is a bottom plan view of a combined hand and finger shield showing my new design;

FIG. 2 is a front elevational view thereof;

FIG. 3 is a rear elevational view thereof;

FIG. 4 is a right side elevational view thereof with the left side elevational view being identical;

FIG. 5 is a top plan view thereof; and,

FIG. 6 is a cross-sectional view taken through FIG. 2 along the line 6—6.
